UNITED STATES PATENT OFFICE

GORGE L. GREGORY, OF McALESTER, OKLAHOMA, ASSIGNOR OF ONE-THIRD TO WILL H. ROBBINS, OF McALESTER, OKLAHOMA

PLOW

Application filed September 13, 1928. Serial No. 305,789.

This invention has for its object the provision of a strong and durable breaking plow in which the point and share will be effectually reenforced and the depth to which the 5 point may enter the ground may be easily regulated.

The invention also has for its object the provision of means whereby the beam will be connected with the mold board so as to brace 10 the same and the handles will be mounted in such a manner that the beam may be readily adjusted to regulate the depth of the cut.

The invention is illustrated in the accompanying drawings and will be hereinafter 15 fully set forth.

In the drawings:

Figure 1 is a side elevation of a plow viewed from the mold board side.

Figure 2 is an enlarged rear elevation, the 20 beam and handles being broken away.

Figure 3 is an elevation viewing the landside side of the plow.

Figure 4 is a horizontal section on the line 4—4 of Figure 3.

25 Figure 5 is an enlarged detail section taken vertically through the slot in the front end of the foot and the adjacent parts about on the line 5—5 of Figure 4.

Figure 6 is an enlarged detail view of the 30 lower end of the standard with the foot, showing the moldboard side of the same.

Figure 7 is a perspective view of the frog.

In carrying out the invention there is provided a beam 1 of approved form provided 35 at its front end with a clevis or other draft device 2 and having its rear end curved downwardly to form a standard 3. The lower end of the standard is formed integral with a foot 4 having an opening 5 through its rear end whereby it may be pivotally attached to the landside and having a slot 6 formed through its front end on an arc concentric with said opening 5. A lateral projection 7 is formed on the foot 4 at the sides of the 40 slot 6 and the inner face of this projection is formed with horizontally extending corrugations or teeth, as shown at 8, the purpose of which will presently appear. The landside 9 is a straight rectangular bar of the usual form disposed in the horizontal plane of the

foot 4 of the standard at the outer side thereof and connected therewith by transverse bolts, as will be understood. Between the foot 4 and the landside is interposed a frog 10 which has a longitudinal portion substantially of the same form and dimensions as the landside and secured to the landside and the standard by the same bolts which connect the landside to the foot 4 of the standard. At its front end the frog is formed with a lateral wing 11 which is shaped to conform to the rear of the mold board 12 and the share 13 and bridges the joint between the share and the mold board, as shown clearly in Figure 2. The share 13 is formed integral with the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 55 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 60 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 65 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 70 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 75 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 80 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 85 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 90 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 95 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2. The share 13 is formed integral with 100 the point 14 and the point is formed with an abrupt rear end abutting the front end of the landside, as shown at 15, the line of merger between the share and the point being curved, as shown at 16, and the frog having a similar curve uniting the wing 11 to the main bar of the frog so that the parts will be very efficiently reenforced, as will be understood upon reference to Figure 2.

washer so as to secure the beam and standard in a set position. The bolt 24 is inserted through the landside, the frog, and the slot 6 in the foot 4 with its head resting in a countersunk seat in the outer side of the landside and its threaded end projecting from the moldboard side of the foot and the projection 7 theron. The washer 22 is then fitted on the end of the bolt with its corrugated face presented to the corrugated face of the projection 7 after which the nut 23 is engaged on the bolt and turned home against the washer.

To the rear side of the mold board, approximately at the center of the same, is secured a strap 25 which has its upper portion twisted somewhat so that one handle 26 may be secured thereto. The other handle 27 is secured to a strap 28 which has its lower end secured to the side of the standard 3 and projects somewhat therefrom at its upper end. This manner of mounting the handles will permit them to be easily removed when necessary without dismantling the working parts 25 of the plow, and the handles are reenforced and prevented from dropping by bracing links 29 which are secured at their front ends to the standard at the point where it merges into the beam and have their rear ends adjustably secured to the respective handles.

It will be readily seen from the foregoing description, taken in connection with the accompanying drawings, that I have provided a very strong and durable plow which is not unduly complicated in its construction. By loosening the nut 23 and the nut on the bolt through the hole 5 in the rear end of the foot, a pivotal movement may be imparted to the foot 4 about said bolt so that the front end of 40 the beam 1 may be adjusted vertically relative to the plow point 14 and, of course, after the beam has been set at the desired angle, the nuts are again turned home. The corrugated construction of the opposed faces of 45 the projection 7 and the washer 22 will relieve the strain on the threads of the bolt 24 and maintain the beam in the position in which it has been set and the depth of penetration by the point 14 may be thus easily 50 regulated without requiring the driver to exert undue pressure upon the handles. The bracket 18 is obviously readily adjustable to accommodate the varying angular relation between the standard 3 and the mold board 55 as the standard is adjusted in the just described manner, and this bracket is located nearer the landside edge of the mold board so that it will aid in resisting the thrust upon the plow. The arcuate brace 17 and the frog 60 10 very effectually reenforce the point and the share and consequently prolong the life of the plow. The described adjustment permits the user of the plow to set the point 14 to make the proper cut under any circumstances and thereby avoid excessive wear upon 65

the point and the share so that the necessity for frequently re-sharpening the point and the share will be avoided.

Having thus described the invention, what is claimed is:

1. In a plow, the combination of a mold board, a standard at the rear of the mold board, a bracket secured to the rear side of the mold board and having a slotted member disposed against the inner side of the standard, 75 said slotted member having a corrugated inner face, a washer fitted against said corrugated and slotted member and mating therewith, and a securing bolt inserted through the standard, washer and said slotted member to 80 adjustably secure the parts together.

2. In a plow the combination of a plow body comprising a mold board, a share and a landside, of a standard provided at its lower end with a foot disposed at the inner side of 85 the landside and extending rearwardly longitudinally thereof, means for pivotally connecting the rear end of the foot with the landside, and means at the front end of the foot for locking the foot in its position of angular 90 adjustment.

3. In a plow comprising a mold board, a share and a landside, a standard provided at its lower end with a foot disposed at the inner side of the landside and extending longitudinally of the same, a lateral projection on the inner side of said foot at the front end thereof, said projection having horizontal corrugations on its inner face and there being an arcuate slot formed through the projection 100 and the front end of the foot, means for pivotally securing the rear end of the foot to the landside, securing means inserted through the landside and through the arcuate slot in the foot and said projection, and 105 handles connected to the standard.

In testimony whereof I affix my signature.
